Primary Examiner — Doris Clark(74) *Attorney, Agent, or Firm* — Zollinger & Burleson Ltd.(57) **CLAIM**

The ornamental design for an adjustable baluster, as shown and described.

DESCRIPTION

FIG. 1 is a perspective view of an adjustable baluster showing a first configuration of my new design;

FIG. 2 is a front elevation view thereof; the rear elevation view being a mirror image thereof;

FIG. 3 is a left side elevation view of thereof; the right side view being a mirror image thereof;

FIG. 4 is a top plan view thereof; and,

FIG. 5 is a bottom plan view of thereof.

Broken lines in the drawings form no part of the claimed design.
